UNITED STATES PATENT OFFICE.

PAUL HERING, OF METHUEN, MASSACHUSETTS, ASSIGNOR TO CROMPTON & KNOWLES LOOM WORKS, OF WORCESTER, MASSACHUSETTS, A CORPORATION OF MASSACHUSETTS.

CLUTCH FOR LOOM PATTERN MECHANISMS.

Application filed March 21, 1927. Serial No. 176,955.

This invention relates to improvements in a driving mechanism for dobby or head motions more particularly of the type known in the trade as the Knowles loom and shown in Patent 134,992 and it is the principal object of the invention to provide means for varying the rate to which the harnesses are moved and also the actual time in which they are moving.

10 The Knowles loom employs an upright shaft which is driven from the bottom shaft of the loom by a variable gearing usually provided with an elliptical gear on the bottom shaft which meshes with an eccentric gear on a stub shaft. The stub shaft has a miter gear which meshes with a second miter gear loose on the bottom of the upright shaft. The harness and box motions of the loom are controlled by the upright shaft and any 15 variation in the rotation of said shaft will be communicated by means of mutilated cylinder gears to the harnesses or boxes. When a hard twist filling is being woven into the cloth it is desirable to close the harnesses as 20 soon as possible after the flight of the shuttle so that the filling will not have time to twist and cause kinks or lay unevenly in the cloth. On the other hand, where the width of the cloth is the maximum for which the 25 loom is designed, as much time as possible must be allowed for the flight of the shuttle before the harness starts to close.

In order to provide for these varying conditions the elliptical and eccentric gears are 30 changed relatively to the upright shaft. This has heretofore been accomplished in an awkward manner by lifting the upright shaft bodily so that the miter gear at the lower end thereof is out of mesh with the 35 miter gear on the stub shaft. The upright shaft is then given a slight angular movement equal to one or more teeth on the miter gears and is then lowered. This procedure requires a partial disassembling of the pattern mechanism and it is an important object 40 of my present invention to provide for changing the angular relation of the upright shaft with respect to the elliptical and eccentric driving gears while the upright shaft is in its 45 usual position.

It is a further object of my invention to provide a removable pin to connect the upright shaft with the miter at the lower end

thereof, said removable pin facilitating the aforementioned adjustment. 55

With these and other objects which will appear as the description proceeds, my invention relates to the arrangements and combinations of parts hereinafter set forth, and more particularly pointed out in the claims. 60

In the accompanying drawings Fig. 1 is a rear elevation of the pattern driving mechanism of a right end drive loom, parts being in section,

Fig. 2 is a detailed section taken on line 65 2-2 of Fig. 1 showing the eccentric pinion and the elliptical gear,

Fig. 3 is an enlarged top plan view of the clutch only, looking in the direction of arrow 70 3, Fig. 1,

Fig. 4 is an enlarged horizontal section of line 4-4 of Fig. 1 showing the collar only,

Fig. 5 is an enlarged horizontal section of line 5-5 of Fig. 1 showing the top of the miter gear which is loosely rotatable on the 75 bottom of the upright shaft, and,

Fig. 6 is a detail of the pin such as connects the collar and miter gear on the upright shaft.

Referring to the drawings, I have indicated loom frame 10 as provided with a head frame 11 in which are journaled upper and lower cylinder shafts 12 and 13, respectively. The bottom shaft 14 is journaled in the frame and has adjustably secured thereto by 80 means of set screws 15 a an elliptical gear 15 which meshes with an eccentric pinion 16 of half the number of teeth, said pinion being keyed or otherwise secured to a stub shaft 17. Said stub shaft extends through 85 and rotates in bearing members 18 and 19 and has keyed to the outer end thereof a miter gear 20. Said bearing 19 is provided with an upwardly extending cup bearing 21 which receives the lower reduced end of the upright shaft 22. Said shaft has at the 90 upper end thereof bevel gears 23 which are operatively connected to the cylinder shafts 12 and 13.

The lower end of the upright shaft 22 has 100 a sliding clutch pin member 24 having a groove 25 by means of which said member may be raised by mechanism not shown. A second miter gear 26 is loosely rotatable on the lower end of shaft 22 and may be held in proper vertical position by means of a collar 105

27 which may be threaded or in any other way secured to shaft 22. The mechanism thus far described is a common construction and may be set forth in the aforesaid 5 patent.

My improvements relate to the means for communicating movement from the miter 26 to the upright shaft 22 and in carrying my invention into effect I provide a collar 40 10 shown in Figs. 1 and 4 and key or otherwise secure the same to the shaft 22 so that said collar and shaft rotate together. The clutch member 24 has removably secured therein a clutch pin 41 which may be of the type shown 15 in Figs. 1 and 6, wherein said pin is shown as having a reduced shank 42 and a threaded upper portion 43 which is received by a correspondingly threaded opening in the sliding clutch 24.

20 The loose miter gear member 26 is provided with a single hole 45 in the upper part thereof, said hole being proportioned to receive the pin 41. Said collar 40 is provided with a plurality of openings 46 which are 25 disposed concentric with and parallel to the axis of the upright shaft 22, and each of said openings 46 is proportioned to receive the reduced shank 42 of the pin 41.

The gear indicated generally at T is that 30 usually employed in the so-called "positive reverse worm" take-up and may include a sleeve S the lower end of which lies closely adjacent to the sliding member 24. When this construction is employed it will be desirable to use the removable pin 41, but if 35 there is sufficient room above said member 24 so that the same may be raised far enough for the pin to lie above the collar 40, then the pin need not necessarily be removable 40 from the member 24.

In operation, the bottom shaft 14 will 45 rotate once every two picks of the loom, but the stub shaft 17 will be given a complete revolution every pick of the loom. The 50 miters 20 and 26 have the same number of teeth so that collar 40 and hence the upright shaft 22 will be given a revolution every pick of the loom. It may be assumed for purposes of explanation that the loom 55 is weaving the widest possible cloth so that the maximum time must be allowed for the flight of the shuttle and it may further be assumed that when the eccentric and elliptical gears are in the position shown in Fig. 60 2 the harnesses will start to move. It will be seen from the relation set forth in Fig. 2 that the upright shaft will be given a slow movement at the start so that the harnesses will start moving slowly to allow the shuttle 65 full time to pass through the shed. This relation of course is accompanied by a definite angular relation between the sliding member 24 and the collar 40, this relation being determined by the hole 46 through 70 which the pin 41 extends. If for any reason

it should be necessary to change the drive of the upright shaft so as to get a different relation between the movement of the harnesses and the flight of the shuttle the pin 75 would be removed and the member 24 moved angularly with respect to the collar 40, the necessary distance, after which the pin could be inserted in another of the holes 46. By 80 turning the shaft 22 the pin will be brought over the hole 45 in the miter gear 26 and the member 24 will slide downwardly to its correct position. This will of course leave the shaft out of time with respect to the bottom shaft, but this may be corrected by loosening the set screws 15^a and making an adjustment 85 of the elliptical gear relatively to the bottom shaft so the upright shaft will be in proper time with respect to the loom.

The result of this adjustment will be not only to vary the rate to which the upright 90 shaft will be turning with respect to the bottom shaft at the time the harnesses start to move but also there will be a change in the absolute time during which the change takes place. It is apparent that the teeth on the elliptical gear nearest the bottom shaft will be 95 moved slower than those which are farthest from said shaft and furthermore it will be seen that more of those teeth which are farthest from the bottom shaft will be included in any given angle than is true of the 100 number of teeth nearest the bottom shaft which can be included in an angle of the same size.

It will be seen that the adjustments described can be effected without disturbing the upright shaft 22 and that any desired fineness of adjustment can be provided depending upon the number of holes 46 which are located in the collar 40.

From the foregoing it will be seen that I have provided means for adjusting a drive for loom pattern mechanisms whereby the rate at which the harnesses are moving at any given instance in the tick may be 110 changed and wherein the absolute time required for the crossing of the harnesses may be varied, these results being achieved while the upright shaft member 22 is in its bearings. Furthermore it will be seen that I have provided an improved clutch pin for 115 loom pattern mechanism rendering the same removable so as to facilitate adjustments.

Having thus described my invention it will be apparent that changes and modifications may be made therein by those skilled in the art without departing from the spirit and scope of the invention, and I do not wish to be limited to the details herein disclosed but what I claim is:

1. In a loom pattern driving pattern mechanism, a driving shaft, a driven shaft, driving connections between the shafts including an elliptical gear adjustably held to the driving shaft meshing with an ec- 130

centric gear forming part of connections, a gear operatively connected to the eccentric gear and loosely mounted on the driven shaft, clutch means to connect the loose gear 5 to the driven shaft, and means to change the angular relation between the loose gear and the driven shaft.

2. In a loom pattern driving pattern mechanism, a driving shaft, a driven shaft, 10 driving connections between said shafts including a third stub shaft, means to drive the stub shaft at a variable rate with respect to the driving shaft, means to alter the angular relation of the stub shaft with 15 respect to the driven shaft and means to adjust the variable gear.

3. In a loom pattern driving pattern mechanism, an elliptical gear mounted thereon and secured thereto in adjusted angular 20 position, a stub shaft, an eccentric pinion secured to the stub shaft and meshing the elliptical gear, an upright driven shaft, a miter gear secured to the stub shaft, a second miter gear loosely rotatable on the 25 upright shaft and meshed with the first miter gear a collar secured to the upright shaft, and means to connect the collar and second named loose miter gear in plurality of angular positions.

30 4. In a loom pattern driving pattern mechanism, a driving shaft, a stub shaft, gearing imposed between said shafts to give the stub shaft a variable speed relatively to the driving shaft, means to adjust the gear-

ing relatively to the driving shaft, a driven 35 upright shaft, driving connections between the stub and upright driven shafts, and means to give said upright and stub shafts a plurality of different angular positions.

5. In a loom pattern driving pattern 40 mechanism, a driving shaft, a driven shaft, a miter gear to be operatively related to the driven shaft, means angularly adjustable with respect to the driving shaft to give said miter a movement variable with respect to 45 the driving shaft, a second miter meshing with the first named miter and loosely mounted on the driven shaft and means to connect said second miter to the driven shaft in a plurality of different angular positions. 50

6. In a loom pattern driving pattern 55 mechanism, a bottom shaft, an upright driven shaft, a gear loosely mounted on the upright driven shaft, connections between said gear and between shaft to give said gear a variable speed with respect to the bottom shaft, a collar hitched to the upright driven shaft and having a plurality of openings thereto, a removable pin secured to the sleeve and proportioned to be received by 60 any one of the openings in the collar and also to be received by an opening in the gear, and means to adjust the connections whereby said gear may be changed angularly with respect to the bobbin shaft. 65

In testimony whereof I have hereunto affixed my signature.

PAUL HERING.
